ELECTRICAL CONNECTOR

Edwin A. Noyes, Chevy Chase, Md., assignor of twenty-five per cent to Stewart K. Brown, Alexandria, and twenty-five per cent to Frank G. Campbell, Arlington County, Va.

Application August 5, 1947, Serial No. 766,298

2 Claims. (Cl. 173—328)

1

This invention relates to electrical connectors and it has for its object to provide a device of this character adapted to make electrical connection with a screwhead or like device, in such manner that secure attachment of the connector to the screw head may be effected and considerable pressure may be exerted between the connector and the screwhead.

The device is primarily intended for use in testing and servicing watt-hour meters under conditions hereinafter set forth.

The invention will be best understood by reference to the accompanying drawing wherein;

Fig. 1 is a front elevation of a standard and well-known meter test block used in connection with the mounting and testing of watt-hour meters.

Fig. 2 is a vertical sectional view upon line 2—2 of Fig. 1 looking in the direction of the arrow.

Fig. 3 is a sectional view illustrating a modified form of screw, with which the device of the invention is adapted to make connection.

Fig. 4 is a sectional view upon line 4—4 of Fig. 6.

Fig. 5 is a transverse sectional view upon line 5—5 of Fig. 2.

Fig. 6 is a plan view of the connector of the invention.

Fig. 7 is a side elevation of one of the connectors showing a protecting insulating sleeve applied to the exterior thereof; and

Fig. 8 is a longitudinal sectional view of a modified form of the invention.

Like numerals designate corresponding parts in all of the figures of the drawings. The advantages of the invention will be best understood by first considering the conditions which have brought about its development. The conventional watt-hour meters commonly employed for measuring the current delivered to the customers of electric power companies must be tested or possibly repaired from time to time. When that is to be done they are removed from their mounting and in order that the service to the customer may not be interrupted during the time that the meter is removed, it has been the practice and is now the practice to utilize short sections of cable with spring clips upon their ends to constitute jumpers by which the connections to the meter may be bridged and the service continued until the meter can be replaced.

To facilitate the testing operation the meters (not shown) are mounted in metal boxes (not shown), and in these boxes and below the meters are mounted meter test blocks such as the one illustrated in Fig. 1. These test blocks are made of hard rubber or other insulating material and

2

they comprise a rear wall 5 and a plurality of fore and aft partition walls 6. The electric cables which conduct the current to and from the meter are indicated at 7, 8, 9 and 10. The bared ends 11 of these cables are bound by screws 12 against the rear walls 13 of heavy copper or other metallic sleeves 14, said screws 12 being threaded into the front walls, 15, of these sleeves. Said sleeves are received in the pockets 16, said pockets being bounded by the division walls 6 upon their sides, the rear wall 5 at their rear sides and a transverse front wall at 17. Connecting straps 18, 19, 20 and 21 which lead downwardly from the meter (not shown) are connected to the sleeves 14 by binding screws 22. Thus, with the meter in place, the connection will be from cable 10, for example, to sleeve 14 and thence through screw 22 to the connecting strap 21 of the meter. The screws 12 are provided with annular grooves 23 just back of their heads 24, these grooves being provided by the manufacturer of the test blocks, for the reception of the conventional spring clips, used upon the jumpers commonly employed to bridge the meter contacts when testing is to be done.

25 The parts so far described are of presently known and widely used meter mountings and connections and the practice described of bridging the contacts with jumpers consisting of short sections of cable and conventional spring clips is the practice that has existed for years and is being followed at the present time.

However this practice has become increasingly dangerous due to the fact that the loads carried by the meters have constantly increased. Thus 35 it is common to find meters carrying loads of 50 amperes, at 220 volts or even more. The contact provided by ordinary, manually squeezable, clips is not sufficient to carry a load of this character without overheating at the points of engagement 40 of the clips with the screws 12. It will be observed that the heads of the screws 12 are set back behind the front edges of the fore and aft walls 6. This is designedly done by the manufacturer to cause the screw heads 24 to lie in what is, in effect, recesses, so that these heads 45 cannot be accidentally bridged by any article extending transversely across the block. However this feature which makes for safety under ordinary conditions introduces an element of difficulty when the meter tester seeks to insert the spring 50 clip into this somewhat restricted space. It is clear that if, after the meter tester had connected one end of the jumper to one of the screws 14 and was attempting to connect the other end to another screw 14, such jumper should 55 slip out of his hand or a second spring clip should slip off of the second screw and fall against the

grounded metal box in which the meter is mounted, a heavy short circuit might be created and serious injury to the meter tester might easily result.

While the area of contact between two surfaces making electrical contact is important, the degree of pressure exerted between said surfaces is even more important and with a view to providing a structure which will not only engage the heads of the screws 14 in such a manner that they cannot possibly be accidentally dislodged, and at the same time to provide a structure in which the contacting surfaces will be brought into forcible engagement with each other, I have devised the device of the invention.

In carrying out the invention I provide a hollow trough-like member 26 the forward end of which has its walls inturned to provide a flange 27, adapted to be slipped into engagement with the annular groove 23 of the head of the screw 12. Trough 26 has affixed thereto a nut 28 into which a pressure screw 29 is threaded. This screw is provided with an operating knob 30 upon its outer end by which the screw may be rotated in the nut and when the screw 29 is screwed up against the screw 12 the flange 27 of the trough 26 is drawn into very forcible engagement with the head 24 of the screw 12. This not only results in bringing about a very firm engagement of the connector with the head of the screw 12, but it insures a very efficient electrical connection between the connector and screw 12.

Note that the flange 27 extends not only along two sides of the screw but across the bottom thereof. Thus it engages with the rear face of the screw head 24 through an arc of considerably more than 180 degrees, whereby an electrical connection of large current passing capacity is effected.

Any desired way may be resorted to of securing the necessary electrical cable to constitute a jumper, to the sleeve or trough 26. One such way is to bend the material of the trough downwardly as indicated at 31 in Fig. 5 to thereby produce two slightly separated metallic portions adapted to have bound between them by a binding screw 32 the bared end 33 of the cable 34 of the jumper. Also any suitable means may be employed for so insulating the connector that it may be grasped by the tester for applying it, without danger of shock. For that purpose I have indicated an insulating sleeve 35 upon the screw and an additional insulating sleeve 36 in Fig. 7. However these insulating sleeves constitute no part of the invention, the invention residing in the means described for bringing about a secure and electrically effective connection between the head of the screw 12 and the trough 26. Therefore, I wish it to be understood that any way may be resorted to of connecting the jumper cable to these elements.

While the device of the invention is primarily intended for use in testing meters it is apparent that it may be employed in other relations, and to indicate that this is the case I have illustrated in Fig. 3 the trough 26 having its flanged end 27 engaged behind the head 24 of a screw 12, or other headed element, with which it is desired to make

electrical contact. The housing is threaded into or otherwise rigidly affixed in the end of a tubular member 41 of insulating material. A second member of insulating material 42 is threaded into the rear end of member 41 and its forward end thrusts against the rear end of tip 40.

When the flange 27a is engaged behind head 24 of screw 12, by passing the screw head laterally through the open side of the housing at 26b, and the member 41 is held against turning with the fingers of one hand and the member 42 is screwed into 41; the pressure created by the screw action is transmitted through tip 40 to screw head 24 and this pressure is utilized to draw the flange 27a strongly against the rear face of the screw head. Thus it will be seen that the structures of Figs. 6 and 8 have the common feature of a flange engaging behind a screw head for more than half of the circumference of said head and a screw threaded part functioning to pull the flange against the rear face of the screw, while securing the whole firmly in place on the screw.

It is to be understood that the invention is not limited to the precise construction set forth but that it includes within its purview whatever changes fairly come within either the terms or the spirit of the appended claims.

Having described my invention what I claim is:

30. 1. An electrical connector for connecting an electric cable to a headed screw comprising a tubular housing element having a lateral opening adjacent one end and an inturned flange at said end, an electric cable having a tip slidably 35 in said housing and a two part member united by screw threads one of the parts being affixed to the housing and the other of said parts acting under the screw threads to thrust said tip forcibly against the rear face of said head, both of the said 40 parts being formed of insulating material.

2. An electrical connector for connecting an electric cable to a headed binding post, said connector comprising two axially aligned members of insulating material having threaded engagement with each other, whereby turning of said parts with respect to each other causes one of said parts, hereinafter referred to as the first part, to move endwise into the other and second part, a housing element projecting axially beyond one end of said second part said housing element having end portions shaped to be engaged behind the head of the binding post by lateral movement of the housing element with respect to the said post, an electric cable having a tip 55 affixed thereto, said cable passing freely through said first part and said tip being slidable in said bearing housing, said tip being of such dimensions with respect to the first part that the inner end of the latter bears against the said tip to 60 thrust said tip forcibly against the head of the post and thereby draw the end portions of the housing forcibly against the rear face of the head of said post.

EDWIN A. NOYES.
